CLAIM

The ornamental design for a mobile patient bed, as shown
and described.

DESCRIPTION

FIG. 1 is a perspective view of a mobile patient bed of the
present application;

FIG. 2 is an enlarged front view of the mobile patient bed;
FIG. 3 is an enlarged rear view of the mobile patient bed;
FIG. 4 is a right side view of the mobile patient bed;
FIG. 5 is a left side view of the mobile patient bed; and,
FIG. 6 is a top view of the mobile patient bed.

In the drawings, the broken lines are for the purpose of
illustrating environment only and form no part of the
claimed design.

1 Claim, 6 Drawing Sheets
